UNITED STATES PATENT OFFICE.

WILLARD D. CRANNEY, OF LOGAN, UTAH.

TIE AND MEANS FOR SECURING A RAIL THERETO.

1,168,483.

Specification of Letters Patent.

Patented Jan. 18, 1916.

Application filed May 26, 1914. Serial No. 840,981.

To all whom it may concern:

Be it known that I, WILLARD D. CRANNEY, a citizen of the United States, and a resident of Logan, in the county of Cache and State of Utah, have invented a certain new and useful Improvement in Ties and Means for Securing Rails Thereto, of which the following is a full, clear, and exact description.

My invention comprises a novel railroad tie and means for securing a rail in position thereon, said attaching means including a portion of the tie itself.

The object of my invention is the provision of simple, efficient and economical means for attaching the rails to a tie—which latter, in its preferred form, comprises a metallic body portion provided with a wooden, shock absorbing, pillow block.

Broadly speaking, the invention consists in providing the tie with lugs or projections adapted to engage bifurcated retaining clamp members which overlie the rail flanges, and in forcing the parts into close engagement by wedging action.

In the single sheet of drawings accompanying this application and forming a part hereof, Figure 1 is a perspective view of one end of a tie, with a portion of a rail secured thereto; Fig. 2 is a cross section of the parts shown in Fig. 1; and Fig. 3 is a perspective view of one of the clamps.

Referring to the drawings, in which like parts are designated by like characters, 5 indicates a channel shaped metallic tie, 6 a wooden pillow block, 7 a section of a rail, and 8, 8, a pair of bifurcated rail securing clamps.

A pair of projections 9, 9, in the present preferred form shown as integral lugs 40 formed by punching out rectangular portions of the flanges of the channel iron, though adapted to be formed in any convenient manner without departing from my invention, extend outwardly from the body 45 portion of the tie in position to be engaged by the lower extremities of the forks 10, 10, of the clamping members, which clamping members are preferably S-shaped in side view as shown in the drawings.

The body portion 11 of the clamping members is so proportioned as to overlie and engage the flange of a rail throughout the length of the clamp and the clamp is further provided with a substantially horizontal lip 55 12 adapted to extend over the pillow block 6 and provided with an opening 13 through

which a spike 14 may be driven to engage the pillow block. The channel flanges of the tie are notched at 15 to allow the rail to rest solely on the pillow block and at the same time to prevent lateral displacement of the rails, the rail flange and the clamping members substantially filling the cut out portion.

In assembling, the pillow blocks are 65 placed in the channels nearer the ends of the ties than in the final position shown in the drawings and the clamping members are hooked over the lugs 9 but swung away from operative position. Then the rail is placed 70 on the pillow blocks and the clamping members swung over its flanges, the parts being so proportioned that an approximate, though loose, fit is thus had. The pillow blocks are slightly wedge shaped in vertical section, as 75 indicated in Fig. 2 of the drawings, and the parts are tightly drawn into engagement by driving the pillow blocks home. Spikes 14 are then driven to firmly hold the parts in position.

If desired the webs of the channels may be punched as shown in Fig. 2 to provide slightly interiorly protruding, springy, teeth 16 which will readily allow the pillow blocks to pass over them in the act of driving home 85 in the direction shown by the arrow A but which, by entering the wood, will aid in preventing their working loose.

Having thus described my invention, what I claim and desire to secure by Letters Patent is:

1. In combination, a rail, a tie having a pair of projections extending laterally from each side thereof, and a pair of bifurcated clamping members adapted to be placed one 95 on each side of said rail to overlie and engage the flanges thereof and to pass under and engage a pair of said projections on opposite sides of the tie, and wedging means adapted to draw the rail and clamping 100 members into close engagement.

2. In combination, a rail, a channeled metallic tie having a pair of projections extending laterally from each side thereof, a pair of bifurcated clamping members adapted to be placed one on each side of said rail to overlie and engage the flanges thereof and to pass under and engage a pair of projections on opposite sides of the tie, and a wedge shaped pillow block adapted to lie 110 within the channel of the tie below the rail and, by being driven home, to force the

clamps into close engagement with said rail.

3. In combination, a rail, a channeled metallic tie having a pair of projections extending laterally from each side thereof at each end, a pair of bifurcated clamping members adapted to lie one on each side of said rail to overlie and engage the flanges thereof and to pass under and engage a pair 10 of projections on opposite sides of said tie, each of said clamping members having a perforated, horizontally extending lip for

the reception of a retaining spike, and a wedge shaped pillow block adapted to lie within the channel of the tie below the rail 15 and, by being driven home, to force the clamps into close engagement with said rail.

In testimony whereof I have hereunto affixed my signature in the presence of two witnesses.

WILLARD D. CRANNEY.

Witnesses:

JAMES G. ELLIOTT,
HARRY B. CADWELL.
